UNITED STATES PATENT OFFICE.

PETER F. BUCHANAN, OF LONDON, ONTARIO, CANADA.

CUP-MAKING MACHINE.

Application filed January 30, 1923. Serial No. 615,843.

To all whom it may concern:

Be it known that I, PETER F. BUCHANAN, a citizen of the Dominion of Canada, and resident of London, in the county of Middlesex and Province of Ontario, Dominion of Canada, have invented certain new and useful Improvements in Cup-Making Machines, of which the following is a specification.

10 This invention has relation to certain new and useful improvements in cup making machines and has for its primary object the provision of a simple and compact form of machine which may be employed for making 15 cups from paper or other suitable material in practically one operation.

The invention has for another object the provision of a cup making machine of the character stated which will operate to cut 20 the circular blanks from a continuous strip fed into the machine and form the circular blanks into complete and finished cups immediately upon cutting of the blanks from the supply of material.

25 The invention has for a further object the provision of a cup making machine of the character stated including cutting and stamping dies of simple construction and operation and which are controlled from a 30 cam shaft, means being also provided in the forming dies to heat the paper blanks from both faces as the blanks are pressed and formed into cups.

35 A further object resides in the provision of a cup making machine of the character stated which includes forming dies constructed in such a manner as to corrugate or crease the blanks as the latter are formed into cups.

40 The invention has for a still further object the provision of a cup making machine of the character stated including simple supporting and guiding means for the dies to assure proper and accurate operation thereof as the material is cut and heated.

45 The invention has for a still further object the provision of a cup making machine of the character stated which is composed of the minimum number of parts of simple and inexpensive construction and arrangement and which may be readily assembled or repaired.

50 With the foregoing and other objects in view as will appear as the description proceeds, the invention consists in the novel

construction, combination and arrangement of co-operating elements as hereinafter more specifically set forth, claimed and shown in the accompanying drawings forming a part of the present application, in which:—

60 Fig. 1, is an elevation of the complete machine.

Fig. 2 is a side elevation thereof, at right-angles to Fig. 1.

Fig. 3 is an enlarged vertical section 65 through the dies and the gathering means for the cutting dies, showing the position of the movable parts as the cutting operation is completed.

Fig. 4 is a view similar to Fig. 3, showing 70 the position of the movable parts as the forming operation is completed and the cup finished from the blanks.

Fig. 5 is a detail vertical section through 75 the forming die or plunger, showing the heating means located therein.

Fig. 6 is an enlarged detail plan of the lower or stationary forming die.

Referring more in detail to the drawings 80 in which similar reference characters designate corresponding parts throughout the several views, 10 designates the base or table of the machine which is mounted on suitable supporting legs 11, preferably located near the corner thereof, as shown in the drawings 85 and connected in pairs by the upper side frame members 12, as shown clearly in Fig. 2. The legs of each pair are also connected near their lower ends by the transverse bracing members 13 through which the 90 bracing rods 14 are extended, near the front and back of the machine. The connected supporting legs 11 also serve to support the upper frame work or side castings 15 having outturned flanges 16 at their lower end 95 which are securely mounted on the upper end of the supporting legs 11, as will be clearly apparent from Figs. 1 and 2. As shown clearly in Fig. 1, the base or table 10 is seated in the lower portion of the upper 100 frame members or side castings 15 and firmly held in position therein.

The upstanding side frame members or castings 15 have their rear edges curved or bevelled at the upper ends thereof, as 105 shown at 17. Suitable castings 18 are carried on the front faces of the upstanding side frame members or castings 15, at the upper end thereof, to support transversely above the centre of the base or table 10 110

the operating cam shaft 19 having the drive wheel 20 mounted thereon, preferably to one side of the machine, as shown in Fig. 1. A clutch pedal 21 is suitably mounted on one of the bracing rods 14 as shown in Figs. 1 and 2 and a rod 22 is pivotally connected at its lower end with the pedal 21, as shown in these views. The upper end of the rod 22 is pivotally connected with the clutch pin locking member 23 of the clutch mechanism 24 provided for the cam shaft 19. A return spring 25 is also pivotally connected with the clutch pin locking member 23 and fastened to the adjacent upstanding side frame member or casting 15, as shown at 26. It will, therefore, be evident to parties familiar with this machine that the clutch pedal 21 may be readily operated to release the cam shaft 19. A movement of the pedal 21 in one direction will serve to withdraw the clutch pin locking member 23 from its normal or functioning position, thereby releasing the clutch mechanism and permitting free operation of the cam shaft 19. As the pedal 21 and parts connected therewith are returned to normal position by means of the spring 25, further rotary movement of the cam shaft 19 will be prevented.

The base or table 10 has a central vertical opening 27 extended therethrough and a larger countersunk opening 28 in its upper face arranged concentrically with respect to the central opening 27. Enlargements 29 are formed on the upper face of the base 30 or table 10 and upstanding guide posts 30 are secured at their lower end in the enlargements 29. These enlargements 29 are suitably spaced from one another, as will be evident by referring to Figs. 1 to 4 inclusive. It will also be seen that the guide posts 30 have spiral lubricant passages 31 in their outer faces, so that the guide posts 30 may be thoroughly lubricated at all times. A plate 32 has enlargements 33 around its periphery and serving as guiding collars riding on the guide posts 30. The purpose of the plate 32 will presently appear.

The lower or stationary female cup forming die 34 is extended through the opening 27 of the base or table 10. This die 34 has an out-turned flange 35 which rests in the countersunk opening 28, as shown clearly in Figs. 3 and 4. The upper face of the flange 35 is inclined slightly outwardly and has the radial ribs 36 which form continuations of the longitudinal ribs 37 formed in the inner face of the main portion of the die 34.

A stationary circular cutting die 38 is secured in the countersunk opening 28 outwardly of the flange 35. This stationary circular cutting die 38 extends above the flange 35 and has a cutting edge 39 for co-operation with the cutting edge 40 of the movable circular cutting die 41, which lat-

ter has an outwardly directed flange 42 at its upper end secured in the under face of the plate 32. This may be readily understood by referring to Figs. 3 and 4. The sleeve 43 has its lower end threaded in the upper side of the plate 32 and the diverging upstanding arms 44 projecting from the upper edge of the sleeve 43 have out-turned upper ends 45 which are secured to the under side of the raising and lowering head 46, suitable fastening members 47 being passed through the ends 45 and into the raising and lowering head 46. The sleeve 43 and movable circular cutting die 41 are of corresponding interior diameter and the plate 32 is provided with a circular central opening 48 of approximately the same diameter. The sleeve 43 and movable circular cutting die 41 are also in alignment with one another and with the central circular opening 48 of the plate 32, as shown in the drawings. The raising and lowering head 46 works in suitable removable guide members 49 which are removably mounted on the upper frame work or side castings 15, along the front edge thereof by suitable securing members 50.

The raising and lowering head 46 is operated in the removable guide members 49 by adjustable rods 51 which are pivotally connected at their lower ends to the raising and lowering head 46, while the cam rings 52 are mounted on the upper ends of said adjustable rods 51. These cam rings 52 enclose cam members 53 on the operating cam shaft 19, so as to cause raising and lowering of the head 46 as the operating cam shaft 19 is rotated. This should be readily apparent from Figs. 1 and 2 of the drawings. It is also apparent that as the raising and lowering head 46 is operated, the plate 32 is moved vertically on the upstanding guide posts 30. Each downward movement of the plate 32 will cause operation of the cutting dies 38 and 41 to cut a circular blank 54 from the strip of material 55 fed between the cutting dies 38 and 41, as shown in the drawings.

The plunger 56 works in the centre of the machine and carries a gradually tapering forming die 57 on its lower end, this die 57 has longitudinal ribs 58 on its outer face to correspond with the ribs 37 of the stationary die 34 in which the die 58 is adapted to operate, as shown in Figs. 3 and 4. The die 57 is slightly smaller than the interior of the die 34 so as to thoroughly co-operate therewith in completing the formation of the cups from the circular blanks. The upper end of the plunger 56 is secured in the collar 59 in a suitable manner, as shown in Fig. 4 and this collar 59 has the upstanding flanges 60 between which is extended the lower end of a sectional operating rod 61 having its lower end pivotally

connected with an upstanding portion 62 of the collar 59, as shown in Figs. 1 and 4. The cam ring 63 is mounted on the upper end of the sectional operating rod 61 and extends around a cam member 64 carried on the operating cam shaft 19 and offset from the cam members 53 preferably to a right angle to the latter. The purpose of this arrangement of the cam members 53 and 64 will later appear.

A collar 65 is mounted on the upper portion of the plunger 56 and secured in adjusted position longitudinally of the latter by a set screw 66 or other suitable means. By proper adjustment of the collar 65, the tension of the spring 67 surrounding the plunger 56 may be readily regulated as the upper end of this spring bears against the under face of the collar 65. The lower end of the spring 67 rests upon the upper end of the upper movable creasing die 68, a reduced upstanding flange 69 being formed on the top of the upper movable creasing die 68 and extending into the lower end of the spring 67. This flange 69 is of proper diameter to permit sliding movement of the plunger 56 therethrough. The main portion of the upper movable creasing die 68 is spaced from the plunger 56, however, and of sufficient size to receive at the proper time the gradually tapering forming die 57, as will be understood by referring to Figs. 3 and 4. The outwardly directed annular flange 70 carried at the lower end of the upper movable creasing die 68 has radial ribs 71 formed on its under face and corresponding with the radial ribs 36 on the flange 35 of the lower stationary female cup forming die 34. The radial ribs 71 and 36 will co-operate in corrugating or creasing the outer portion of the blank during formation of the cup from the blank. A bearing washer 72 is mounted on the upper face of the flange 70 to form a bearing for the lower end of the helical expansion spring 73 which encloses the upper movable creasing die 68 and also portions of the plunger 56 and the spring 67. The upper end of the spring 73 bears against the washer 74 secured in the upper portion of the sleeve 43 by supporting bolts 75 or the like extending inwardly through the side of the sleeve 43 and into depending lugs 76 carried by the washer 74. By referring to Figs. 3 and 4 it will be apparent that the springs 67 and 73 work alternately. This is due to the arrangement of the cam members 53 and 64 on the operating cam shaft 19. It is desirable to have the heavy spring 73 acting to press downwardly the upper movable creasing die 68 at the time of operation of the cutting dies 38 and 41 to cut a new blank or set of blanks from the single set or plurality of sets of paper or other material in position between the cutting dies 38 and

41. It is to be understood that one or more blanks may be cut with each operation of the cutting dies 38 and 41 according to the number of sheets of material being fed to the machine. As the cutting die 41 is raised, the pressure of the spring 73 is decreased and the tension of the spring 67 increased by downward movement of the plunger 56. This will permit of gradual releasing of the edge of the blank or blanks after creasing or corrugating between the flanges 35 and 70. As the formation of the cups from the blanks continues, the creases or corrugations will be continued between the gradually tapering forming die 57 and the interior of the lower stationary female cup forming die 34. The result will be the delivery of finished cups from the lower end of the lower or stationary female cup forming die 34.

In order that the blanks may be properly heated during formation of the cups, an electric heating member 77 is provided within the gradually tapering forming die 57 with the current conducting wire 78 extending from the heating member 77 through the plunger 56 and out of the open upper end thereof, as shown in the drawings, particularly Fig. 5 which discloses the fact that the plunger 56 and gradually tapering forming die 57 are hollow. The current conducting wires 78 connect with a suitable switch 79 having positive and negative main supply wires 80 connected thereto. Current conducting wires 81 connecting with the wires 78 are extended to an electric heating member 82 extending around the lower or stationary female cup forming die 34, preferably below the base 10, as shown in the drawings. It is, therefore, apparent that the blanks will be heated from both surfaces during formation of the cups from the blanks, provided the switch 79 is closed to complete a circuit through the wires 78 and 81.

It is believed the complete construction and operation of the machine may now be understood from the foregoing paragraphs taken in connection with the accompanying drawings without further detailed description. It may be briefly stated, however, that the complete operation will be automatic and it will be simply necessary to feed the strips of material to the machine and operate the pedal 21. The switch 79 should be closed over one of the switch points 79' to assure proper heating of the blanks 54 cut from the strips of material, the heating members 77 and 82 providing for proper heating of the blanks from either surface thereof. As the operating cam shaft 19 rotates, the plate 32 will be reciprocated on the upstanding guide posts 30 while the raising and lowering head 46 reciprocates in the removable guide members 49. Move.

ment of the strips of material through the machine is temporarily stopped for each cutting and forming operation of the machine. As the raising and lowering head 46 and the plate 32 move downwardly, the movable circular cutting die 41 cuts through the material, thereby producing one or more circular blanks 54 which are gripped around their edges between the flanges 35 and 70, as shown clearly in Fig. 3. At this time the spring 73 is fully compressed while the spring 67 is expanded and the gradually tapering forming die 57 is completely enclosed in the upper movable creasing die 68, and is above the new blanks. As the raising and lowering head 46 and plate 32 move upwardly and the spring 73 expands to relieve the pressure on the flange 70, the plunger 56 is forced downwardly against the central portions of the blanks 54, forcing them into the lower or stationary female cup forming die 34. This also results in compressing the spring 67 and retaining the upper movable creasing die 68 in lowered position to permit only a gradual releasing of the edges of the blanks 54 from between the flanges 35 and 70. The ribs 37 and 58 of the dies 34 and 57 respectively, registering properly with one another will serve to continue the creasing operation started by the ribs 36 and 71 of the flanges 35 and 70 respectively, thereby assuring a fully and properly corrugated or creased side or body for each completed cup discharged from the lower end of the lower or stationary female cup forming die 34. This corrugating or creasing and forming operation is considerably facilitated by the heating of both surfaces or sides of the blanks through the medium of the heated dies 34 and 57. After the plunger 56 has moved to its lowermost position, it is again raised to its uppermost position, releasing the tension of the spring 67 and returning the die 57 to position within the upper movable creasing die 68. All of these parts are raised a sufficient distance to avoid the strips of material and permit further feeding thereof between the cutting dies 38 and 41 before a return of the cutting die 41 to its lower-most or operated position during which return the working edge of the cutting die 41 passes through the strips of material and thereby provides a new set of blanks as disclosed in Fig. 3. This operation of the machine may be repeated or continued as long as strips of material are fed into the machine. The operation of the various parts of the machine will not interfere with the current conducting wires 78 and 81, owing to the arrangement of the wires and the manner of connecting the same with the heating members 77 and 82.

While this machine is designed principally for making paper cups, it is evident that

the machine may be employed to make ramekins, candy and cake containers and other articles of various sizes, as desired. The predetermined size of the article to be produced will govern the size of the dies and other parts of the machine. Furthermore, the shape and character of the dies may be varied, as desired.

While the preferred embodiment of the invention has been shown and described, it is to be understood that minor changes in the details of construction, combination and arrangement of co-operating elements may be resorted to within the scope of what is claimed without departing from the spirit of the invention.

What I claim as new is:

1. In a cup forming machine, a female die having an upper fluted flange, a plunger die cooperating with said female die, a creasing die cooperating with said fluted flange and means for exerting a resilient pressure upon said creasing die and gradually releasing said pressure during operation of the machine.

2. In a cup forming machine, a female die having an upper fluted flange, a creasing die cooperating with said fluted flange, a strong spring acting upon said creasing die, a shearing element, means for reciprocating said shearing element and compressing said spring, a weaker spring also engaging said creasing die, a plunger die cooperating with said female die and adapted for compressing said weaker spring upon its downward movement.

3. In a cup forming machine, a female die having a fluted flange, a creasing die cooperating with said fluted flange, a plunger cooperating with said female die, a reciprocating shearing element, and yielding elements acting upon said creasing die and alternately acted upon by said shearing element and plunger die.

4. In a cup forming machine, a lower forming die having an upper fluted flange, an upper creasing die, cooperating with said flange, a tapering plunger die working within said upper and lower dies, means for exerting a resilient pressure on said upper creasing die and gradually relieving the pressure thereon during the operation of the plunger, a base, a lower stationary shearing element on said base and surrounding said lower die, and an upper shearing element surrounding said upper die and adapted for cooperation with said stationary shearing element.

5. In a cup forming machine, the combination with blank shearing mechanism, of blank creasing mechanism, cup forming mechanism, means for imparting a yielding pressure on said creasing mechanism during the operation of said shearing mechanism, and means for applying a weaker yielding

pressure on said creasing mechanism during the operation of said cup forming mechanism.

6. In a cup forming machine, the combination with mechanism for shearing paper blanks, of mechanism for creasing said blanks, cup forming mechanism, and resilient means alternately compressed by said shearing mechanism and cup forming mechanism for applying pressure to said creasing mechanism.

7. In a cup forming machine, a pair of cooperating forming dies, creasing mechanism, means for applying a relatively strong pressure to the creasing mechanism during the creasing operation, and decreasing said pressure during the cup forming operation.

8. In a cup forming machine, a lower creasing die, an upper creasing die, and resilient members of different intensity acting on said upper die.

9. In a cup forming machine, a lower creasing die, an upper creasing die, and means alternately acted upon for applying different pressures upon said upper creasing die.

10. In a cup forming machine, cup forming dies, creasing dies, and yielding means acting on said creasing dies for creasing a cup blank and allowing it to be readily withdrawn from the creasing dies by the action of the forming dies.

11. In a paper cup forming machine, the combination with a female die, of a creasing die cooperating with said female die, a plun-

ger, and means for applying pressure to the creasing die in advance of the operation of the plunger and means whereby said pressure is diminished upon the operation of the plunger.

12. In a paper cup forming machine, the combination with a pair of reciprocable members, having successive downward movements, a stationary die and a movable die, means for applying pressure upon said movable die upon the downward movement of the first reciprocable member and diminishing said pressure during the downward movement of the second reciprocable member.

13. In a paper cup forming machine, a pair of cooperating dies, means for yieldingly pressing said dies together, a plunger die for forcing the cups through said dies, the pressure on said dies being diminished when the cup is being forced therethrough.

14. In a paper cup forming machine, a stationary female die, a creasing die cooperating with said female die, a plunger die for forcing the cups through said female die, and regulated pressure means acting upon said creasing die.

15. In a paper cup forming machine, the combination with mechanism for creasing and forming a paper cup, a part of said mechanism being adapted for ejecting said cup and a variable pressure means acting on said mechanism.

In testimony whereof, I affix my signature.

PETER F. BUCHANAN.
